L. I. YEOMANS,
BORING MACHINE,
APPLICATION FILED DEC. 12, 1918.

Patented July 8, 1919.

3 SHEETS - SHEET 3.

UNITED STATES PATENT OFFICE.

LUCIEN I. YEOMANS, OF CHICAGO, ILLINOIS, ASSIGNOR TO AMALGAMATED MACHINERY CORPORATION, OF CHICAGO, ILLINOIS, A CORPORATION OF DELAWARE.

BORING-MACHINE.

1,309,389.

Specification of Letters Patent.

Patented July 8, 1919.

Application filed December 12, 1918. Serial No. 266,408.

To all whom it may concern:

Be it known that I, LUCIEN I. YEOMANS, a citizen of the United States, residing at Chicago, in the county of Cook and State 5 of Illinois, have invented a certain new and Improved Boring-Machine, of which the following is a specification.

In a gun-boring machine, the bearings for the head-stock spindle and the boring 10 bar must be accurately alined. The great length of such a machine, however, has made it difficult to obtain such alinement. The object of the present invention is to provide a machine for use in accurately 15 babbetting and boring out the various bearings in a gun-boring or analogous machine.

In the accompanying drawings, Figure 1 is a side elevation of a boring machine embodying my invention. Figs. 2 and 3 illustrate portions of the feeding mechanism. Fig. 4 is an end elevation. Fig. 5 is a sectional view taken in the plane of line 5—5 of Fig. 4.

In the drawings, 3 indicates two parallel 25 finished carriage ways of a gun-boring or similar machine. 5 is a combination mandrel and boring bar for use in babbetting and boring the various alined bearings (not shown) of the machine. The means for 30 rotating, advancing and retracting the bar 5 comprises a carriage 20 capable of being slidably supported and guided by the ways 3 and of being lifted off said ways after the bearings have been bored. The means 35 for moving the carriage 20 upon the ways 3 comprises a screw 21 fixed at one end to a bracket or cross-piece 22 (Fig. 2), said bracket having flanges 23 that overlie the inner portions of the ways 3. 24 40 are clamping plates which are clamped to the lower surfaces of the inner portions of the ways 3 by means of bolts 25. The screw 21 is engaged by an internally-threaded sleeve or nut 26 (Fig. 3) which is rotatably 45 mounted in a bearing 27 upon the lower side of the carriage 20. The sleeve 26 is held against endwise movement with relation to the carriage by means of a flange 28 and a nut 29.

50 An electric motor 30 mounted upon the rear end of the carriage 20 furnishes power for revolving the bar 5 and the feed-nut 26. On the armature shaft of the motor is a pinion 31 that meshes with a gear wheel

32 fixed on a drive shaft 33 mounted in 55 the carriage 20. The shaft 33 carries a clutch 34, the loose element of which is rigidly connected to a pinion 35. The pinion 35 meshes with a spur gear wheel 36 60 which is rotatably mounted upon a spindle 37 extending parallel with the shaft 33. Rigid with the spur gear wheel 36 is a 65 pinion 38 that meshes with a spur gear wheel 39 that is loose on the shaft 33. A 70 pinion 40 fixed to the spur gear wheel 39 meshes with a spur gear wheel 41 which is fixed upon the spindle 37. The bar 5 is coupled in any suitable manner to the forward end of the spindle 37.

75 It will be seen that when the clutch 34 is thrown in, power will be communicated from the motor 30 to the bar 5, through the train of reduction gears 31, 32, 35, 36, 38, 39, 40 and 41.

Means is provided for moving the carriage 20 upon the ways 3 at two different speeds. The means for moving the carriage at low speed comprises a pinion 42 fixed upon the spindle 37 and meshing with a pinion 43 mounted upon a stub shaft 44 in the carriage 20. Pivottally mounted upon the shaft 44 is a bracket 45 that carries a pinion 46 which meshes with the pinion 43. When the bracket 45 is in the position shown 85 in Fig. 4, the pinion 46 meshes with a spur gear wheel 47 which is rotatably mounted on the carriage 20. Fixed to the spur gear wheel 47 is a pinion 48 which meshes with a spur gear wheel 49 that is fixed to the 90 feed nut 26. A handle 50 on the bracket 45 provides means for swinging the bracket 45 to carry the pinion 46 into and out of mesh with the spur gear wheel 47. Any suitable means may be provided for holding the bracket 45 in and out of operative 95 position.

The means for rotating the feed nut 26 at high speed comprises a sprocket wheel 51 (Fig. 4) which is loosely mounted upon 100 the shaft 33 and is arranged to be connected thereto by means of a clutch 52. The sprocket wheel 51 carries a chain 53 which extends to a sprocket wheel 54 mounted upon a shaft 55 in the carriage 20. Rigid with the sprocket wheel 54 is a pinion 56 that meshes with the spur gear wheel 47.

Means is provided for throwing the clutches 34 and 52 alternately into operation,

This means comprises a rod 57 which is longitudinally slideable in bearings on the carriage 20, said rod having fixed thereto an arm 58 for operating the clutch 34 and an arm 59 for operating the clutch 52. A hand lever 60 is pivoted between its ends to the carriage 20 at 61 and engages a flanged sleeve 62 fixed on the shifter rod 57. 63 is a latch which is pivoted to the carriage 10 at 64 and adapted to lie in contact with the shifter rod 57 between the bearings 65 and a collar 66 on the shifter rod.

The operation is as follows:

When the bearings of a gun-boring machine are to be formed, the carriage 20 is placed upon the finished ways of the gun-boring machine, and the screw 20 is secured to said ways by means of the bracket 22, clamping plates 24 and bolts 25. The bar 20 5 having been connected to the spindle 37, power is communicated to the motor 30. When the hand lever 60 is in the position shown in full lines in Fig. 1, the shaft 33 revolves idly, no motion being communicated to the boring bar 5 or to the feed nut 26. When the lower end of the hand lever 60 is swung to the right, as viewed in Fig. 1, the shifter rod 57 is slid to the left, thereby throwing in the clutch 34, whereupon rotation is imparted to the boring bar 5. If the bracket 45 be in the position shown in Fig. 4, the carriage 20 also will be moved toward the work at low speed.

When it is desired to move the carriage 35 20 in the opposite direction, the bracket 45 is raised to disengage the pinion 46 from the spur gear wheel 47, the safety latch 63 is raised clear of the collar 66, and the hand lever 60 is swung in the direction to slide 40 the shifter rod 57 to the right, as viewed in Fig. 1, thereby throwing out the clutch 34 and throwing in the clutch 52. The sprocket chain 53 is thereby driven, thus communicating relatively rapid movement to the feed 45 nut 26 and causing the carriage 20 to move away from the work. The rapid drive may also be employed to advance the carriage rapidly by reversing the direction of rotation of the motor.

50 When the bearings of the gun-boring machine have been formed, the feed screw 21 may be released from the ways 3, the bar 5 disconnected from the spindle 37, and the carriage 20 lifted off the ways.

I claim as my invention:

1. A machine for boring a bearing of a machine having carriage ways, said first-mentioned machine having, in combination, a carriage adapted to be slidably supported and guided by said ways, a carriage-feed screw and a coöperating nut, one of said screw elements being rotatably carried by the carriage, means for clamping the other of said screw elements to the carriage ways, a boring-bar spindle on the carriage, and a 65 motor mounted on the carriage and operatively connected to the spindle and the rotatable screw element.

2. A machine for boring a bearing of a machine having two parallel carriage ways, 70 said first mentioned machine having, in combination, a carriage adapted to be slidably supported and guided by said ways, a carriage-feeding element on the carriage, a co-acting feeding element, means for detachably connecting said coacting element to the carriage ways at a point forward of the carriage, a drive shaft and a boring-bar spindle on the carriage, a connection between the shaft and the spindle, a drive connection between the spindle and the feeding element on the carriage, a drive connection between the drive shaft and the last mentioned feeding element, and a motor mounted on the rear end of the carriage and operatively connect- 85 ed to the drive shaft.

3. A machine for boring a bearing of a machine having carriage ways, said first mentioned machine having, in combination, 90 a carriage adapted to be slidably supported and guided by said ways, a carriage-feeding element on the carriage, a coacting feeding element, means for detachably connecting said coacting element to the carriage ways, a drive shaft and a boring-bar spindle on 95 the carriage, a clutch-controlled connection between the shaft and the spindle, a connection between the spindle and the feeding element on the carriage for driving said element in one direction at low speed, and a 100 clutch-controlled driving connection between the drive shaft and the last mentioned feeding element for driving said element in the opposite direction at a higher rate.

In testimony whereof, I have hereunto set 105 my hand.

LUCIEN I. YEOMANS.
